CROWN BLOCK

Harry P. Wickersham, Huntington Park, and
Erwin Burns, Los Angeles, Calif.

Application November 6, 1935, Serial No. 48,513

6 Claims. (Cl. 254—190)

This invention relates to well drilling equipment and relates more particularly to a crown block for use on a well derrick. A general object of the invention is to provide a simple, practical and improved crown block.

Another object of this invention is to provide a crown block comprising a plurality of individual sections each section carrying a sheave and each section being capable of dependably carrying the load imposed on its sheave.

Another object of this invention is to provide a sectional crown block of the character mentioned that may be readily built into a unit or crown block embodying as many sheaves as required for any particular installation.

Another object of the invention is to provide a practical crown block that may carry or include large sheaves. Each section of the crown block of the invention carries only one sheave and, therefore, the sheaves may be large in diameter.

Another object of this invention is to provide a crown block for use on a well derrick that is very simple and easy to install. In mounting or arranging the crown block of the present invention on the top of a well derrick it is unnecessary to assemble any parts and it is only required that the several sections each carrying their individual sheaves be bolted together and secured to the water table of the derrick.

Another object of the invention is to provide a crown block of the character mentioned that is very inexpensive of manufacture. The individual sections carrying the main sheaves being identical and each comprising a simple, integral body or frame are inexpensive and provide for great economy in the construction of the crown block.

A further object of this invention is to provide a crown block in which the stresses of operation are better distributed than in typical crown blocks embodying long bearing pins or shafts each carrying several sheaves.

The various objects and features of our invention will be fully understood from the following detailed description of typical preferred forms and applications of the invention, throughout which description reference is made to the accompanying drawings, in which:

Fig. 1 is a side elevation of the crown block provided by this invention with a portion broken away to appear in vertical cross section. Fig. 2 is a reduced elevation view of one end of the crown block being a view taken substantially as indicated by line 2—2 on Fig. 1. Fig. 3 is a

reduced elevation view of the other end of the crown block being a view taken as indicated by line 3—3 on Fig. 1. Fig. 4 is a reduced vertical detailed sectional view taken substantially as indicated by line 4—4 on Fig. 1. Fig. 5 is an enlarged fragmentary vertical sectional view taken as indicated by line 5—5 on Fig. 4. Fig. 6 is an enlarged fragmentary horizontal sectional view taken as indicated by line 6—6 on Fig. 4. Fig. 7 is an enlarged fragmentary sectional view taken as indicated by line 7—7 on Fig. 4, and Fig. 8 is a fragmentary view showing a form of the invention in which a secondary frame section is interposed between certain of the frame and sheave sections.

The crown block provided by this invention includes, generally, a plurality of sections A each carrying a sheave 10 and a section B carrying two sheaves 11 and 12.

The assembly of the sections A comprises the major or main portion of the crown block embodying the large sheaves 10 which carry the line running to the traveling block. The several sections A are identical in construction and design and each is individually supported on the derrick. In accordance with the invention there may be any desired number of sheave carrying sections A, the number of sections A depending upon the particular installation for which the crown block is required. As the several sections A are identical we will proceed with a detailed description of one section A, it being understood that this description is to apply to the several like sections A.

Each sheave carrying section A of the crown block includes a body or frame 14 adapted to be arranged on the water table or top of the derrick and operating to support a sheave 10. The frame 14 is designed and shaped to best carry the loads imposed on the sheave 10. In accordance with the invention the frame 14 is an integral or one-piece member comprising two upwardly convergent legs 15 and a substantially horizontal head 16 extending between and connecting the upper ends of the legs 15. The legs 15 and the head 16 are channel shaped in transverse cross section and have their open sides or channels 17 facing inwardly. Openings or slots 18 are provided in the legs 15 and the head 16 to facilitate the threading of the line on the sheave 10 of the section A. Feet 19 are provided on the legs 15 and are recessed as at 20 to receive and properly seat on the upper webs of supporting beams 21, or the like. Openings 22 may be provided in the

feet 19 to pass bolts 23 for securing the frame 14 to the beams 21.

The frame 14 of the section A includes webs extending across its interior to support the sheave 10. Two pairs of spaced webs 24 extend diagonally downwardly and inwardly from the upper corners of the frame 14 and two pairs of spaced webs 25 extend diagonally upwardly and inwardly from the feet 19 or the lower ends of the legs 15. Spaced horizontal webs 26 extend inwardly from each frame leg 15. The webs 24, 25 and 26 are integral parts of the frame 14 and extend inwardly to integrally join bearing bosses 27. The bosses 27 are parallel and spaced apart horizontally and are provided with aligned horizontal openings 28.

The sheave 10 of each section A is supported in the section frame 14 to carry a line or cable. The sheave 10 is received between the spaced sets 20 of webs 24, 25 and 26 with its hub 29 received between the spaced bearing bosses 27. The sheave 10 may be large in diameter to have its peripheral edge portion received in the channels 17 of the legs 15 and the head 16. A suitable groove 30 is provided in the periphery of the sheave 10 to carry the line. The channels 17 of the legs 15 and the head 16 receive the sheave 10 with suitable clearance and the legs and head assist in preventing the line or cable from jumping from the sheave.

The invention includes practical effective means for rotatably supporting the sheave 10 in the section frame 14. A shaft or bearing pin 31 is arranged or supported in the openings 28 of the bosses 27. Screws 32 are threaded into openings 33 in the bosses 27 and cooperate with notches 34 in the pins 31 to hold the pins against movement. A hardened bushing 35 is arranged in the opening 36 of the sheave hub 29. An anti-friction roller bearing 37 is interposed between the hardened bushing 35 and the bearing pin 31 to rotatably support the sheave 10 on the pin. The sheave hub 29, the hardened bushing 35 and the end washers 38 of the bearing 37 are received 40 between the spaced bosses 27 which hold them against endwise movement. The bearing pin 31 rotatably supporting the sheave 10 may be tubular as illustrated in the drawings.

The invention includes means for lubricating the rotatable mounting of the sheave 10. The bearing pin 31 has a lubricant port 40 discharging at its periphery. An opening 41 is provided in one of the frame bosses 27 and a lubricant conduit or pipe 42 extends through the opening 41 to conduct lubricant under pressure to the port 40. The lubricant pipe 42 extends to the outer side of a leg 15 where it is provided with a grease gun fitting 43 or other suitable means for receiving lubricant under pressure. The lubricant supplied through the pipe 42 and the port 40 effectively lubricates the rotatable mounting of the sheave 10.

The several sections A constructed as just described are adapted to be arranged in side by side relation on the supporting beams 21 and are preferably connected together in the manner to be hereinafter described and with the section B constitute the crown block structure. The number of sections A embodied in the crown block may be varied to suit the particular installation. The sections A are preferably arranged on the beams 21 or other supports in side by side relation with their sheave supporting pins 31 in axial alignment.

The section B of the crown block includes the

sheave 11 for carrying a line to be operated by a cat-head to handle objects and tools at the derrick floor and further embodies the sheave 12 for carrying a line to be operated by the sand wheel for handling bailers and the like. The section B includes a body or frame 44 carrying the two sheaves 11 and 12.

The frame 44 is an integral structure comprising two upwardly convergent legs 45 and a substantially horizontal head 46 extending between and connecting the upper ends of the legs 45. The legs 45 and the head 46 are channel shaped and have their open sides or channels 47 facing inwardly. Feet 48 are provided on the lower ends of the legs 45 and have their under sides recessed or shaped to properly seat on the upper webs of the beams 21. Horizontally spaced intermediate or central bosses 49 are provided on the head 46. Webs 50 extend diagonally from the bosses 49 to join the legs 45 at their feet 48. Sets of spaced webs 51 extend diagonally downwardly and inwardly from the points of joinder of the legs 45 and the head 46 and join the webs 50 at spaced bosses 52. Horizontally spaced webs 53 extend between and connect the bosses 52. The section B may be arranged at either end of the assembly of the plurality of the sections A or may be interposed between any two adjacent sections A and its bosses 49 are substantially concentric with the bosses 27 of the frames 14 when in proper position.

The sheave 11 is arranged in the frame 44 with its hub 54 concentric with one pair of bosses 52 and the sheave 12 is arranged in the frame 44 with its hub 54 between and concentric with the other pair of frame bosses 52. The sheaves 11 and 12 have suitable peripheral grooves 55 for carrying the lines and the legs 45 and the head 46 have openings or slots 56 to facilitate the threading of the lines on the sheaves 11 and 12. The peripheral portions of the sheaves 11 and 12 extend into the channels 47 of the legs 45 and the head 46 so that the legs and head assist in preventing the lines from jumping from the sheaves.

The means for rotatably mounting the sheaves 11 and 12 in the frame 44 of the section may be similar to the means for rotatably mounting the sheaves 10. Tubular bearing pins 57 are arranged in the openings 58 of the bosses 52. Plates or washers 59 are arranged against the outer sides of the bosses 52 to engage the outer ends of the pins 57 to prevent outward movement and displacement of the pins. Bolts 60 may be passed through openings 61 in the washers 59 and openings 62^a in the webs 25 of the adjacent end section frame 14. Nuts 62 are threaded on the bolts 60 to clamp the bearing pins 57 against endwise movement and to connect the web structure of the frame 44 with the web structure of the adjacent frame 14. Pins 63 are threaded into openings 64 in the bosses 52 and cooperate with notches 65 in the bearing pins 57 to lock the pins against turning and endwise movement. Hardened bushings 66 are arranged in the hubs 54 of the sheaves 11 and 12 and anti-friction roller bearings 66 may be interposed between the hardened bushings 66 and the bearing pins 57 to rotatably support the sheaves on the pins.

Means is provided for lubricating the rotatable supports or mountings of the sheaves 11 and 12. The lubricating means includes lubricant ports 67 in the bearing pins 57 discharging at the peripheries of the pins. An opening 68 is provided in one boss 52 of each pair of bosses and receives

a pipe 69. The pipes 69 conduct the lubricant under pressure to the ports 67. The pipes 69 extend to the outer sides of the legs 45 where they are provided with grease gun fittings 70 or other suitable means for supplying them with lubricant under pressure.

The section B constructed as just described may be arranged at either end of the assembly of the sections A. In practice the sheaves 11 and 12 of the section B are considerably smaller in diameter than the sheaves 10 of the sections A and the section B may be appreciably smaller than the sections A, as illustrated throughout the drawings. The assembly of the plurality of sheave carrying sections A and the section B are preferably connected to form a single crown block structure. The means for connecting the assembly of the sections A of the section B comprises rods 71 passed through horizontal openings 72 in the legs 15 and horizontal openings 73 in the legs 45 of the section B. The legs 15 of the sections A and the legs 45 of the section B may have suitable bosses at the openings 72 and 73 to reinforce them and to slightly space the adjacent abutting sections. Nuts 74 are threaded on the opposite ends of the rods 71 to clamp the several frames 14 of the sections A together and to clamp the frame 44 of the section B against the frame 14 of the adjacent end section A. The means for connecting the assembly of the sections A and the section B may further include a rod 75 passed through an opening 76 in the head 46 of the frame 44 to extend through the aligned tubular bearing pins 31. A plate or washer 77 is arranged against the boss 27 at the other end of the crown block and the rod 75 passes through an opening in the washer 77. Nuts 78 are threaded on the opposite ends of the rod 75 to clamp together the several frames 14 of the sections A and to clamp the frame 44 of the section B against the frame 14 of the adjacent end section A. The rods 60 described above assist in securing the section B to the adjacent end section A. The bolts 23 may be passed through the openings 22 in the feet of the frames 14 of the sections A and similar bolts 80 may be passed through openings 81 in the feet 48 of the frame 44 to secure the section B to the beams 21. The sections A and the section B may be secured to the beams 21 either before or after the assembling and connecting of the several sections A and the section B by means of the bolts 71 and 75.

It is believed that the utility and practicability of the crown block provided by the present invention will be readily understood from the foregoing detailed description. The crown block comprising the multiplicity of like or identical sections A and the single section B is very simple and inexpensive of manufacture and is readily adaptable for various installations. The sections A are simple units each comprising an integral frame 14 and a single sheave 10. The frames 14 are independent and each carries its own load as imposed on it by the sheave 10. As the sections A each comprise a single sheave 10 the sheaves 10 may be large in diameter. The individual sections A and the section B may be independently assembled before their arrangement on the crown block so that the installation of the crown block does not require the assembling of any parts and merely necessitates the attachment of the sections A and B to the supports or beams 21 and the bolting together of the several sections. The sheaves 10 and the sheaves 11 and 12 are

independently supported for rotation by simple dependable mounting means. The bearing pins 31 and 57 each carry a single sheave and are supported at their opposite ends immediately adjacent the point of bearing of the sheaves so that the stresses imposed on them are evenly distributed and are directly imposed on the frames of the sections A and B. The section B carrying the sheaves 11 and 12 may be mounted at either end of the assembly of the sections A as desired, or may be interposed between two adjacent sections A of the assembly. As the several sections A are identical the section B may be mounted at either end of an assembly of sections A comprising any number of sections. Each section A and the section B operates independently of the other sections to carry the load imposed on it and the crown block does not include complicated and expensive supports, etc. for carrying superimposed sheaves.

Having described only a typical preferred form and application of our invention we do not wish to be limited or restricted to the specific details herein set forth, but wish to reserve to ourselves any variations or modifications that may appear to those skilled in the art or fall within the scope of the following claims:

Having described our invention, we claim:

1. A crown block including an assembly of a plurality of sections arranged in side by side relation, each section comprising a frame, and a sheave carried by the frame, and a section at one end of the assembly comprising a frame, and two sheaves carried by the frame.

2. A crown block including an assembly of a plurality of sections arranged in side by side relation, each section comprising a frame, and a sheave carried by the frame, the sections being arranged with their sheaves in axial alignment, and a section at one end of the assembly comprising a frame, and sheaves on the frame at opposite sides of the plane of the aligned sheaves.

3. A crown block comprising a plurality of identical sections, each comprising a frame, and a single sheave carried by the frame, the sections being arranged in side by side relation with their sheaves in axial alignment, and a section adapted to be arranged at either end of the assembly of the sections and comprising a frame, and spaced sheaves carried by the frame.

4. A crown block comprising a plurality of identical sections, each comprising a frame, and a single sheave carried by the frame, the sections being arranged in side by side relation with their sheaves in axial alignment, a section adapted to be arranged at either end of the assembly of the sections and comprising a frame, and spaced sheaves carried by the frame, and means for connecting the said sections and the section.

5. A crown block including a plurality of like sections, each section comprising a frame and a sheave rotatably supported by the frame, and a section interposed between two of the first named sections and comprising a frame, and spaced sheaves rotatably supported by the frame.

6. A crown block including a plurality of identical sections each comprising a frame, and a sheave carried by the frame, the sections being adapted to be arranged with their frames in aligned and side by side relation, and a section interposed between two of the first named sections comprising a frame and spaced sheaves carried by the frame.
